UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed December 10, 1921. Serial No. 521,329.

To all whom it may concern:

Be it known that I, MALCOLM L. COSSITT, a citizen of the United States, residing at Alameda, in the county of Alameda and 5 State of California, have invented certain new and useful Improvements in Manifolding Attachments for Typewriters, of which the following is a specification.

My invention relates to the class of mani- 10 folding attachments for typewriters and like type-impact machines, in which one or more manifolding members, associated with suitable carrying devices on the platen-carriage of the machine, are adapted to be moved into 15 and out of functional position in the line of type-impact.

My present invention comprises means for storing or housing said manifolding members within the typewriter platen, and adapting 20 them to be drawn out therefrom to their association with their carrying devices, in order to present successive sections for use, so that each exhausted section may be torn off and replaced by drawing out its successor. It also comprises novel means for automatically changing the position of the mani- 25 folding section in use with respect to its width, at each line-spacing of the platen, so that it may be used over practically its entire width. It also comprises novel de- 30 tails of construction and arrangement, all of which will hereinafter fully appear, by reference to the accompanying drawings, in which—

35 Fig. 1 is an end view of my manifolding attachment, showing one of the manifolding-ribbon carrying-arms down in functional position and another elevated out of use.

Fig. 2 is a front elevation, broken, of the 40 same.

Fig. 3 is a plan-view, broken, of the same, the platen being in section to show its housing chamber, and the mounting of the ribbon-spools therein.

45 Fig. 4 is an end sectional view taken on the line 4—4 of Fig. 3.

Fig. 5 is a section of the platen through its chamber, on the line 5—5 of Fig. 2.

50 Fig. 6 is a perspective view of the ribbon-guide which lies within the platen chamber.

Fig. 7 is a cross section on the line 7—7 of Fig. 8 showing a modification in storing the manifolding ribbons.

55 Fig. 8 is a section of the same on the line 8—8 of Fig. 7.

1 indicates the platen-carriage of a typewriter and 2 the platen, having a shaft 3 to rotate it for line spacing in the usual manner.

In one end of the platen 2 is made a chamber 2' and within this chamber is housed a spool 4 freely rotatable upon the platen-shaft 3, Figs. 3 and 5. There may be a plurality of these spools, here shown as two, each being independent of the other. Mounted upon a fixed bar 5 of the platen-carriage is a bracket 6, one near each end, as shown in Fig. 3. The free end of one of these brackets is secured as by screws 6', Fig. 1, to the head of a sleeve 6'' lying within the chamber 2' of the platen. Within the sleeve and secured thereto is a hollow guide-member 7 which surrounds the spools 4. This guide member is provided with a peripheral slit 7' at an angle to its axis. Fig. 6. In this case there are two such slits, as shown. The sleeve 6'' and guide member 7, because of their connection with the bracket 6 mounted on the fixed bar 5, are non-rotatable, and the platen has therefore its usual line-spacing rotation 80 on its own shaft axis without any interference offered by said sleeve and guide-member, though all parts being mounted on the platen-carriage, move together from side to side of the machine as usual. 85

Upon each spool 4 is wound a manifolding ribbon 8 of any suitable nature. One of these ribbons is drawn from its spool and passes through one of the slits 7' of the guide member 7, by which it is diverted 90 into a course parallel with the platen axis, as seen in Fig. 3, and thence out through an opening 9 in the head of the sleeve 6''. The other ribbon has a similar course through the other slit 7' which is guarded by a cleat 95 7'' to carry the ribbon to a different plane in order to avoid interference with the first ribbon. Upon the brackets 6 at each end are pivoted at 10' the carrying arms 10, two being here shown at each end. These arms, 100 one at each end, are connected in pairs by the rods 11 to effect their movement in unison. The arms at one end are shown as formed with handles 12 to conveniently move them about their pivots at 10', and 105 said arms are provided with guide slots 13 and impaling lugs 14. The opposite arms have similar impaling lugs 14', as seen in Figs. 2 and 4. The manifolding ribbons drawn out from their housed spools are first 110

carried through the guide slots 13 of the handled arms 10, and thence in front of the impaling lugs 14 and thence over to the impaling lugs 14' of the other arms, and by 5 being temporarily impaled upon said lugs are held under proper tension parallel with the platen. By simply disengaging them from the impaling teeth they may be drawn out repeatedly, in order to present successive 10 sections in functional position, as preceding sections become exhausted through use, said worn out sections being cut or torn off at or beyond the farther arm.

In operating the attachment, the arms 10 15 are normally elevated to hold the ribbon out of the way. If but one carbon copy be desired, a pair of arms are turned down, as shown in Figs. 1 and 2, to carry their ribbon into functional position in the line of type- 20 impact. The slack of the ribbon between its place of emergence from the platen and the adjacent arm as indicated in Fig. 1, permits the movement of the arms. When the section of the ribbon between the arms is used 25 up, the operator releases it from the impaling lugs and then draws the ribbon forward until a fresh section, paid off from the spool housed within the platen chamber, is brought between the arms and is again im- 30 paled. The used section is now cut or torn off and discarded. If two carbon copies are required, both pairs of arms, with their corresponding ribbons, are moved into functional position, as shown in Fig. 3.

35 In order to provide for an adjustment of the ribbon in the direction of its width, at each line spacing of the platen, so that when in use it may be presented to the blows of the type over several longitudinal lines, I 40 have provided a cam 15 on the platen shaft 3, as shown in Fig. 4. The ribbon carrying arms 10 rest, when down in functional position, on this cam which thus also serves as a stop to limit the arms and define the prop- 45 er position of their ribbons.

50 Springs 16 serve to yieldingly hold the arms on the cams. When the shaft 3 is rotated to turn the platen for a line space, the cam 15 will cause or permit the arms 10 to move, up or down as the case may be, thus slightly changing the width relation of the ribbon to the line of type impact; and, according to the contour of the cam, this change may be in successive slight steps up 55 and down, whereby the ribbon may be utilized over practically its whole width. In Figs. 7 and 8 is shown a modification in the storing of the ribbons within the chamber of the platen. In this form, apertured cas- 60 ings 17 are supported within the platen, and in these casings the ribbons are stored in fan-fold shape, and are adapted to be drawn out therefrom.

65 It will now be seen that my manifolding attachment when assembled is a simple,

compact and self-contained structure in which all the parts are carried by the specially adapted platen. In applying the device for use with existing machines, all that is necessary is to remove the old platen of the 70 machine, and substitute my platen therefor, with its associated manifolding parts.

I claim:—

1. A manifolding attachment for typewriters comprising a chambered platen; and a 75 manifolding member housed within the chamber of the platen and adapted to be drawn therefrom for presentment in functional position in the line of type-impact.

2. A manifolding attachment for type- 80 writers comprising a chambered platen; a manifolding member housed within the chamber of the platen and adapted to be drawn therefrom for presentment in functional position in the line of type impact; 85 and means associated with the platen-carriage of the machine for holding said withdrawn member.

3. A manifolding attachment for type- 90 writers comprising a chambered platen; a 95 manifolding member housed within the chamber of the platen and adapted to be drawn therefrom for presentment in functional position in the line of type impact; and means associated with the platen-carriage of the machine for holding said withdrawn member, and moving it into and out of said position.

4. A manifolding attachment for type- 100 writers comprising a chambered platen; a manifolding member housed within the chamber of the platen and adapted to be drawn therefrom for presentment in functional position in the line of type impact; and a pair of movable, spaced arms associat- 105 ed with the platen carriage of the machine to receive and hold said withdrawn member and move into and out of said position.

5. A manifolding attachment for type- 110 writers comprising a chambered platen; a 115 manifolding member housed within the chamber of the platen and adapted to be drawn therefrom for presentment in functional position in the line of type-impact; and a pair of movable, spaced arms associat- 120 ed with the platen carriage of the machine, each of said arms having a guide with im- 125 paling teeth to releasably hold said withdrawn member under tension and move it into and out of said position.

6. A manifolding attachment for type- 125 writers, comprising a chambered platen; a fixed bracket carried by the platen-carriage of the machine and having a guide-member housed within the chamber of the platen; a manifolding ribbon within and guided by 130 said member to adapt it to be drawn out from the chamber of the platen for present- 135 ment in functional position in the line of type-impact; and means carried by the

platen-carriage of the machine for holding said withdrawn ribbon.

7. A manifolding attachment for typewriters, comprising a chambered platen; a fixed bracket carried by the platen-carriage of the machine and having a guide-member housed within the chamber of the platen; a manifolding ribbon within and guided by said member to adapt it to be drawn out from the chamber of the platen for presentation in functional position in the line of type-impact; and means carried by the platen-carriage of the machine for holding said withdrawn ribbon, and moving it into and out of said position.

8. A manifolding attachment for typewriters comprising a chambered platen, a fixed bracket carried by the platen-carriage of the machine and having a guide-member housed within the chamber of the platen; a manifolding ribbon within and guided by said member to adapt it to be drawn out from the chamber of the platen for presentation in functional position in the line of type-impact; and a pair of spaced arms movably connected with the bracket to receive and hold said withdrawn ribbon and move it into and out of said position.

9. A manifolding attachment for typewriters comprising a chambered platen having a shaft for turning it; a spool mounted for independent rotation upon said shaft within the chamber of the platen; and a manifolding ribbon mounted upon the spool and adapted to be drawn out from the platen-chamber for presentation in functional position in the line of type impact.

10. A manifolding attachment for typewriters comprising a chambered platen having a shaft for turning it; a spool mounted for independent rotation upon said shaft within the chamber of the platen; a non-rotatable guide member within said chamber; and a manifolding ribbon mounted upon the spool and adapted to be drawn through said guide member and out from the platen-chamber for presentation in functional position in the line of type impact.

11. A manifolding attachment for typewriters comprising a chambered platen having a shaft for turning it; a spool mounted for independent rotation upon said shaft within the chamber of the platen; a non-rotatable guide member within said chamber;

a manifolding ribbon mounted upon the spool and adapted to be drawn through said guide member and out from the platen-chamber for presentation in functional position in the line of type impact; and a pair of movable spaced arms associated with the platen-carriage of the machine for holding said withdrawn ribbon and moving it into and out of said position.

12. In a manifolding attachment for typewriters, and in combination with a platen having a shaft for turning it for line spacing; a manifolding member; means for carrying said member into and out of functional position in the line of type-impact; and a cam on the platen-shaft upon which said carrying means freely rest and adapted at each line spacing of the platen, to move said carrying means to vary the width relation of said manifolding member to the line of type impact.

13. In a manifolding attachment for typewriters, and in combination with a platen having a shaft for turning it for line spacing; a manifolding member; a pair of pivotally mounted, spaced arms adapted to carry the manifolding member into and out of functional position in the line of type-impact; and a cam on the platen-shaft upon which said arms freely rest when the manifolding member is in functional position for moving said arms at each line spacing of the platen, to vary the width relation of said member to the line of type impact.

14. In a manifolding attachment for typewriters, a pair of spaced arms carried by the platen carriage of the machine, said arms being provided with teeth for releasably impaling a length of manifolding ribbon carried between said arms under tension.

15. In a manifolding attachment for typewriters, a manifolding ribbon; means for carrying said ribbon on the platen-carriage of the machine, adapting it to be drawn out for presentation in the line of type impact; and a pair of spaced arms carried by the platen carriage for holding said drawn out ribbon between them, said arms having teeth for releasably impaling the ribbon to hold it under tension.

In testimony whereof I have signed my name to this specification.

MALCOLM L. COSSITT.
